UNITED STATES PATENT OFFICE.

DAVID J. SCOTT, OF PLAINFIELD, NEW JERSEY, ASSIGNOR TO ISABELLA SCOTT AND DAVID J. SCOTT, EXECUTORS OF THE ESTATE OF WALTER SCOTT, DECEASED, DOING BUSINESS UNDER THE NAME OF WALTER SCOTT & COMPANY, OF PLAINFIELD, NEW JERSEY.

PRINTING MACHINE.

Application filed February 4, 1926. Serial No. 85,819.

This invention relates to printing machines, and has for its main object and feature the provision of means associated with two printing couples, one for printing and the other for perfecting a web, whereby a web can be successfully printed at will by either couple first.

In the art of printing, as practiced at the present time, it is customary to drive one of the cylinders of a printing couple from a drive shaft and to drive not only the other cylinder of the couple from the first one but also to drive the cylinders of the second couple from the cylinders of the first couple. Owing to the fact that it is impossible to avoid backlash in the gears and that the effect of this backlash is cumulative, that is, the greater the number of gears the greater the effect, it will be understood that, in a construction where one couple is driven from another, the pull of the cylinders of the different couples is not equal. As a consequence, it has been the practice to lead the web to be printed and perfected first to the couple that is nearest the driving shaft and then to the couple more remote from the driving shaft; that is, the web passes first to the couple exerting the greater pull or having the least backlash and then to the couple exerting the lesser pull or having the greater backlash. If the web is always threaded through the couples in the order named, satisfactory printing will be accomplished because the couple exerting the greater pull is drawing from a web roll that responds to the pull of the cylinders. If, however, it is now attempted to thread the web in the reverse order, that is: first through the cylinders exerting the lesser pull and then through the cylinders exerting the greater pull, then the web is apt to break because of the unyielding character of the paper feed of the cylinders exerting the lesser pull and the no less unyielding character of the paper feed of the cylinders exerting the greater pull, or, if the web does not break but is pulled bodily between the cylinders exerting the lesser pull then the printing becomes smeared. It will therefore be seen that, if the gearing can be so arranged that either printing couple exerts substantially the same pull, it is immaterial how the web is threaded. In printing from type it is usually of no consequence which side of the

paper is printed first, but in printing from half-tone or Ben Day plates it has been found that one side of the paper, especially news-print paper, will receive a better impression than the other. It is therefore not only a great convenience to be able to thread the paper in different ways, but it likewise improves the quality of the printing and is therefore highly desirable in every way.

Accordingly the invention consists in providing means whereby the two printing couples can be so driven as to exert substantially an equal pull on the web and in the other features of construction hereinafter disclosed in a preferred embodiment in the drawings in which:

Fig. 1 is a diagrammatic view of two printing couples and associated elements showing the web threaded in one direction, and

Fig. 2 is a diagrammatic view similar to Fig. 1 showing the web threaded in the other direction.

1 and 2 indicate two printing couples each consisting here of two cylinders designated by 3, 4, 5 and 6. 7 indicates a horizontal driving shaft and 8 and 9 are two vertical shafts. Separate gearing is arranged between the horizontal shaft and the two vertical shafts here taking the form of bevel gears 10, 11 and 12, 13. Vertical shaft 8 drives printing couple 1 by means of bevel gears 14 and 15, and vertical shaft 9 drives printing couple 2 by means of bevel gears 16 and 17. It is clear therefore that printing couple 1 will exert the same pull as printing couple 2, because the number of gears in each train of gears is the same, and it will be understood that, if there were not separate transmission means to each couple but instead one couple were driven from the other, then the pull exerted by the two couples on the web would be different.

18 indicates web guides by means of which the web may be directed initially to either couple.

Spur gears 19 and 20 interconnect the cylinders of the two couples but it will be understood that these gears in nowise defeat the advantage of the separate drives; their object is to prevent the two couples from becoming circumferentially displaced or out of time in case one couple is disconnected from its driving means. If while such cou-

ple is disconnected it should be attempted to turn it the other couple would likewise be turned.

I claim:

• A printing mechanism including: two printing couples, one for printing and the other for perfecting a web, a horizontally disposed drive shaft, two vertically extending shafts, independent gearing connecting

10 the drive shaft with each vertical shaft,

gearing for driving one couple from one vertical shaft and the other couple from the other vertical shaft, and gearing directly connecting the couples aforesaid, independently of the vertical shafts, to maintain their 15 circumferentially timed relation.

Signed at Plainfield, in the county of Union and State of New Jersey this 28th day of January, 1926.

DAVID J. SCOTT.
